Patented Apr. 13, 1915.

UNITED STATES PATENT OFFICE.

CHARLES F. MENZEL AND GUY C. CARPENTER, OF ROXBURY, MASSACHUSETTS.

PLIERS.

Specification of Letters Patent. Patented Apr. 13, 1915.

1,135,830.

Application filed June 8, 1914. Serial No. 843,838.

To all whom it may concern:

Be it known that we, CHARLES F. MENZEL and GUY C. CARPENTER, citizens of the United States, residing at Roxbury, in the county of Suffolk and State of Massachusetts, have invented certain new and useful Improvements in Pliers, of which the following is a specification.

This invention relates to new and useful 10 improvements in pliers, and has for its principal object to provide a pair of pliers which are particularly adapted for use in making chains of wire or similar material.

Another object of the invention is to provide 15 a pair of pliers which will effectively spread the links of the chain in order that additional links may be added if so desired.

A further object of the invention is to provide 20 a pair of pliers in which the links may again be compressed to their normal condition and any danger of accidental displacement thereof is eliminated.

With these and other objects in view, the 25 invention consists in the novel combination and arrangement of parts which will be fully set forth in the following specification and accompanying drawings, in which,

Figure 1 is a side view in elevation of a 30 pair of pliers constructed in accordance with this invention, Fig. 2 is an end view thereof, and Fig. 3 is a longitudinal sectional view taken on line 3—3 of Fig. 1.

Referring now to the drawings by characters of reference, the numerals 1 and 2 designate 35 as entireties the two coöperating members forming the pliers. The element 1 is provided at one end with the enlargement 3 which is cut away as at 4. This cut-away portion extends angularly as at 5 and 40 terminates in the enlargement 6 as clearly illustrated in Fig. 1. A suitable angular extension 7 is formed at the free terminal of the enlargement and terminates at its free end in the upstanding tooth 8, which 45 is provided with the inwardly extending angular face 9, the use of which will appear as the description proceeds.

A plurality of transverse ribs are formed 50 on the inner faces of the enlargement 6 and thus forms the jaw member, which is arranged to coöperate with the jaw member which will be more fully hereinafter described.

The member 2, hereinbefore referred to, is 55 provided with the enlargement 11 which is

cut away in a manner similar to the cut-away portion 4, and is arranged to fit the cut-away portion to permit the members 1 and 2 to be pivotally secured as at 12. A suitable angular extension 13 is formed on 60 the enlarged portion 11 at its free terminal and said angular extension is provided with a plurality of ribs 14 at its inner face which are arranged to coöperate with the ribs 10, hereinbefore mentioned. A suitable 65 angular extension 15 is formed at the free terminal of the portion 13 and terminates at its upper end in the extension 16, which is provided with the recess 17 in which the link of the chain which is being opened, is 70 adapted to rest.

It will be apparent from the foregoing that in use the link of the chain which is to be opened is placed so that one end rests in the recess 17 hereinbefore mentioned, and 75 the free edge of the tooth 8 of the pliers, is inserted between the body portion of the link and the rearwardly turned end. Upon opening the pliers, it will be apparent that the link will be forced open, and thus a new 80 link may be substituted. After the desired number of links have been placed in position, the link which has been opened is then placed between the jaws of the pliers so that they will rest in the spaces between the ribs 85 10 and 14, whereupon pressure is applied to the handles of the pliers and it will become evident that the link will be closed and any accidental displacement of the remaining 90 portions of the chain will be eliminated.

While in the foregoing there has been shown and described the preferred embodiment of this invention, it is to be understood that such changes may be made in the combination and arrangement of parts as will fall within the spirit and scope of the invention as defined in the appended claim.

Having thus described our invention, we claim:

A pair of pliers comprising handle portions, enlargements formed on the handle portions, said enlargements being offset with relation to the handle portions and being hinged together near the point where they join the handle portions, jaws formed by the 100 enlargements, a longitudinal extension at the free end of one of the jaws, said extension being of less width than the jaw and being provided with a notch in its outer face, the inner face of the jaw being con- 110

cave, a longitudinal extension on the coöperating jaw, said extension being provided with a convex inner face arranged to co-operate with the concave face of the coöperating jaw and an inclined outer face formed on the extension, said inclined outer face forming an edge at the terminal of the extension which is arranged to engage between the bent over portions of the links of

a wire chain to force the same outwardly ¹⁰ and thereby open the link.

In testimony whereof we affix our signatures in presence of two witnesses.

CHARLES F. MENZEL,
GUY C. CARPENTER.
